UNITED STATES PATENT OFFICE.

GEORGE F. MCGILL, OF CHICAGO, ILLINOIS.

CHANGE-MAKER.

1,398,299.

Specification of Letters Patent. Patented Nov. 29, 1921.

Application filed April 19, 1920. Serial No. 374,855.

To all whom it may concern:

Be it known that I, GEORGE F. MCGILL, a citizen of the United States, and a resident of the city of Chicago, in the county of Cook and State of Illinois, have invented certain new and useful Improvements in a Change-Maker; and I do hereby declare that the following is a full, clear, and exact description of the same, reference being had to the accompanying drawings, and to the numerals of reference marked thereon, which form a part of this specification.

The invention relates to an improved type of a change maker having a plurality of coin tubes for holding coins of different denominations, each of said tubes having associated therewith a lever actuated arm provided with a counterweighted ejector adapted to eject a coin and cause said coin to operate a counter-weighted means to retract a slideable coin support to permit discharge of the coin, said means adapted to act automatically to return the coin support into normal position.

It is an object of this invention to provide a change maker wherein the friction between the ejecting mechanism parts is practically negligible.

It is also an object of the invention to provide a change maker with a gravity acting ejector, and a gravity controlled retractable coin stack support.

Another object of the invention is to provide a coin tube with a movable gravity controlled coin support adapted during the ejection of a coin to support the rear portion of a coin until the front portion has been moved clear of stationary supports to permit the coin to drop through a discharge opening.

A further object of the invention is to provide a coin holder with a pivoted gravity acting ejector adapted during an ejecting operation to engage the lowermost coin of a stack of coins and eject the same and then tip slightly to permit the ejecting tip to frictionally slide outwardly underneath the remaining lowermost coin until said coin is cleared to permit the ejecting tip of the ejector to be elevated by gravity into normal ejecting position.

It is an important object of this invention to construct a change maker wherein the coin to be ejected normally rests on comparatively small supporting surfaces to reduce the frictional resistance to a minimum during an ejecting operation of a coin.

Other and further important objects of this invention will be apparent from the disclosures in the specification and drawings.

The invention (in a preferred form) is illustrated in the drawings and hereinafter more fully described.

On the drawings:

Figure 1 is a front elevation of a change maker embodying the principles of this invention.

Fig. 2 is a side elevation thereof.

Fig. 3 is an enlarged section partly broken away and taken on line 3—3, of Fig. 1, showing parts in elevation.

Fig. 4 is a fragmentary detail taken on line 4—4, of Fig. 3.

Fig. 5 is a fragmentary detail taken on line 5—5, of Fig. 3.

Fig. 6 is a sectional view taken on line 6—6, of Fig. 3.

Fig. 7 is a section taken on line 7—7, of Fig. 3.

Fig. 8 is a sectional view partly broken away and taken on line 8—8, of Fig. 3.

Fig. 9 is an enlarged detail taken on line 9—9, of Fig. 8.

Fig. 10 is an enlarged detail taken on line 10—10, of Fig. 6.

As shown on the drawings:

The change maker comprises a box or casing comprising a bottom plate 1, side plates 2 and 3, a removable back plate 4, a lower front plate 5, an upper inclined front plate 6, and a rearwardly inclined table plate 7. The upper end of the casing between the upper inclined plate 6 and the back plate 4 is closed by a suitable top to prevent access to the interior of the casing. The table plate 7, extends rearwardly and abuts the back plate 4. The casing is supported on legs 8. Formed in the lower rear corner of the side plate 2, is an opening 9. Secured to the inner surface of the table plate 7, is an inclined trough or chute 10, which slants downwardly and rearward starting from the side wall 3, to permit the lower or discharge end 11, thereof to project through the opening 9, and curve rearwardly with the open end thereof disposed above a coin receiver or cup 12, mounted at the rear of the casing.

Mounted on the front surface of the inclined upper front plate 6, is a plate 13, to

which is rigidly secured by rivets 14, or other suitable means a plurality of adjacently disposed parallel inclined coin tubes 15, of different sizes for holding stacks of 5 coins 16, of different denominations. Each coin tube 15, is cut away at the lower margin to afford an opening 17. Provided in the table plate 7, below each of the coin tubes 15, is a round discharge opening 18, a portion 10 of which is positioned to extend to the front of the plate 6, while the rest of said opening is positioned to the rear of the plate 6, as clearly shown in Fig. 6. Each discharge opening 18, is provided with a front 15 guide slot 19, and a rear guide slot 20, formed in the table plate 7, and diametrically alined with one another. Each coin tube 15, has the lower side margins bent inwardly to afford stationary coin supporting 20 flanges 21, the coin supporting surfaces of which are comparatively small for the purpose of minimizing the friction between a coin and said supporting flanges when a coin is ejected. The coins 16, are deposited 25 in the top of a coin tube and drop to the bottom of the tube with the lowermost coin resting on the supporting flanges 21, and in a plane with the outlet opening 17. Angle stops 22, are secured on the table plate 7, to 30 one side of the front guide slots 19, for the purpose of preventing outward movement of the lowermost coins in the coin tubes.

Since the coin ejecting mechanisms for each of the coin tubes are alike the description will be confined to one of said mechanisms. Securely mounted on the plate 6, behind the coin tube 15, is an angle bracket or lug 23, to which is pivotally connected by a pivot pin 24, the angle portion of a bell- 35 crank comprising a short arm 25, and a long arm 26, integrally formed at an angle with said short arm. The lower end of the bell-crank arm 26, projects through a slot 27, formed in the front end of a slidable guide 40 plate 28, and through the discharge opening 18. Formed on the end of the short bell-crank arm 25, is a weight 29, adapted to act as a means for normally holding the slidable plate 28, in its forward position to permit the rear portion of the lowermost coin 45 16, in the tube 15, to rest on a movable coin supporting tip 30, integrally formed on the front end of the slidable guide plate 28. Secured on the rear portion of the table 50 plate 7, are a pair of guide strips 31, bent to afford guide grooves for the slidable plate 28.

The ejecting mechanism for each coin tube is mounted in the lower chamber of the 55 casing and comprises a pair of spaced upright apertured lugs 32, which are integrally formed or rigidly secured on the inner surface near the front margin of the casing bottom plate 1. Supported by the 60 lugs 32, is a pin 33, on which is pivotally

mounted the angled portion of a bell-crank embracing an upwardly projecting long arm 34, and a short arm 35. The upper end of the long arm 34, is slotted to receive a gravity acting ejector 36, supported on a 70 pivot pin 37. One end of the ejector is pointed or tapered to form an ejecting tip which normally projects upwardly through the front slot 19 in the table plate 7. The other end of the ejector is provided with a 75 weight 38, for normally holding the ejecting tip in its elevated position. Secured on the casing bottom 1, is one end of a spring 39, the other end of which is secured to the arm 35, to normally hold said arm elevated, so that the free end thereof will hold an operating lever 40, in raised position as shown in full lines in Fig. 3. The lever 40, has the inner end thereof pivotally connected to a pin 41, supported by lugs 42, secured on the 80 casing bottom plate 1, to the rear of the front lugs 32. The other or free end of the lever 40, projects outwardly through a vertical slot 44 in the arm 34, and through a slot 45 provided for the purpose in the lower 85 front wall 5, of the casing. A button or key 43, is mounted on the outer end of the lever 40, and said button is provided with a numeral to indicate the denomination of the 90 coins in the coin tube 15.

95 The operation is as follows:

Coins of different denominations, such as pennies, nickels, dimes, quarters and half dollars, are manually stacked in the respective coin tubes, with the lowermost coin in 100 each stack resting on the stationary supporting flanges 21, and the movable supporting tip 30, of the respective tubes.

Normally the slidable plate 28, associated with a coin tube, is held in its forward position as shown in Fig. 3, with the supporting tip 30, projecting into the coin tube to engage underneath the rear portion of the lowermost coin in the tube. The plate 28, is held in place by the bell-crank member 105 25-26, the weight 29, acting to hold the lower end of the arm 29, in its forward position. The normal position of the ejector 36, is shown in full lines in Fig. 3. The spring 39, acts to hold the bell-crank arm 110 35, and the lever 40, in their elevated position.

Normally the tip of the ejector 36, projects upwardly through the table plate slot 19, in front of the lowermost coin 16. To 115 eject the lowermost coin from underneath a stack of coins in a coin tube, the button 43, is depressed, thereby forcing the lever 40, to swing downwardly into the dotted line position of Fig. 3. Downward movement 120 of the lever acts to depress the short bell-crank arm 35, against the action of the spring 39. As the arm 35, swings downwardly the long arm 34, is simultaneously 125 swung rearwardly, thus moving the ejector 130

ing tip of the ejector 36, rearwardly against the lowermost coin. The lowermost coin is thus forced to slide rearwardly on the stationary supporting flanges 21. The supporting tip 30, and the plate 28, move rearwardly with the coin, at the same time pulling the lower end of the long bell-crank arm 26, rearwardly and elevating the weighted arm 25. The rear portion of the coin is supported during its movement by the supporting tip 30, until the coin is brought into a position to register with the discharge opening 18, in the table plate 7. The coin is then permitted to drop through the opening 18, into the inclined chute 10. The deposited coin falls or slides downwardly by gravity through the chute 10, and is deposited into the receiving cup 12.

Simultaneously with the discharge of a coin, the weight 29, acts automatically to force the plate 28, forwardly to again position the supporting tip 30, underneath the stack of coins remaining in the chute 15. With the release of the button 43, the compressed spring 39, acts automatically to elevate the arm 35 and the lever 40, to normal position. Upward movement of the arm 35, causes the arm 34, to move outwardly from the dotted line position of Fig. 3, into the full line position. The ejector 36, being pivoted in the upper end of the arm 34, is adapted to have the upper end or tip swung downwardly so that said ejector tip can slide outwardly underneath the lower coin in the coin tube. As soon as the ejector tip has cleared the front of the lower coin the ejector weight 38, acts automatically to again raise the tip end of the ejector into normal position, ready to engage the next coin.

Attention is directed to the fact that the ejecting mechanism is very easily operated, partly due to the fact that the supporting surfaces of the stationary coin supporting flanges 21, are smooth and comparatively small. The return of the movable supporting tip 30 to normal position is substantially simultaneous with the ejection of a coin.

If desired the movable support 30, may be integrally formed or secured on the lower end of the long bell-crank arm 26, and the guides 31 and the slidable plate 28, may be omitted.

I am aware that numerous details of construction may be varied through a wide range without departing from the principles of this invention, and I therefore do not purpose limiting the patent granted otherwise than necessitated by the prior art.

I claim as my invention:

1. A change maker comprising a tube for holding a stack of coins, stationary means for supporting said coins, an apertured slid- able coin support, gravity acting means pro- jecting therethrough for normally holding

said slidable coin support in position underneath said coins, and a counterweighted ejector for discharging the lowermost coin in said stack from the tube.

2. In a change maker the combination with a tube holding a stack of coins, a pivoted bell-crank, a spring for holding the same in released position, an ejector pivoted on one end of said bell-crank, a weight on one end of said ejector for holding the other end in position to permit ejection of the lowermost coin from said tube, and a pivoted lever contacting with the other end of said bell-crank whereby the lever is held in an elevated position ready for use.

3. In a change maker the combination with a coin holding tube, of flanges integrally formed in said tube for engaging two opposite margins of a coin in said tube to support said coin, ejecting means, and a movable coin support adapted to be moved by said coin during the ejection thereof by said ejecting means.

4. In a change maker the combination with a coin holding member, of flanges in said member for engaging the margin of a coin in said tube to support said coin, gravity controlled means adapted to contact with and eject said coin from the holding member, and a gravity controlled support for said coin adapted to be moved by the coin until the same is discharged.

5. In a change maker the combination with a coin holding tube, of a coin ejecting means associated therewith, means formed in said tube for supporting the coins therein, a slid- able coin support, a bell-crank pivoted on said tube and engaging said slidable support, and a weight on said bell-crank adapted to normally cause the bell-crank to hold the slid- able support projected into said tube underneath the lowermost coin therein.

6. In a change maker the combination with an apertured plate, of a coin tube mounted thereabove, flanges formed in said tube above said plate for supporting coins in said tube, a movable coin support, a gravity acting means for holding the movable support projecting into said tube underneath the lowermost coin, and an ejector mechanism adapted to slide the lowermost coin and the movable support out of the tube to discharge said lowermost coin through the aperture in said plate, said gravity acting means adapted to automatically return the movable support to normal position.

7. A change maker comprising a casing, a plate forming a part thereof and having an opening therein, a tube mounted above said plate for holding a stack of coins, a discharge chute in said casing for receiving coins from said tube as they are discharged through said opening, a gravity controlled slidable support adapted to engage underneath the lowermost coin in said tube, a spring con-

trolled member in said casing, a lever for operating the same, and a gravity controlled ejector on said member adapted to move the lowermost coin and the slidable support into 5 a position wherein the lowermost coin is adapted to drop through the plate opening into the discharge chute.

8. In a change maker the combination with a coin tube, of a spring controlled slotted 10 bell-crank, a gravity controlled ejector pivotally supported in one end of the bell-crank, and a lever projecting through the bell-crank for operating the spring controlled bell-crank to cause the ejector to discharge the 15 lowermost coin in said tube.

9. In a change maker the combination with a coin tube, of a pivoted bell-crank having a slot therein, a spring for holding the bell-

crank in normal position, a pivoted lever projecting through the bell-crank slot adapted 20 to be held in an operating position by said bell-crank, a button on the end of said lever to facilitate operation of the lever, an ejector pivotally mounted on the bell-crank, and a weight at one end of the ejector for holding 25 the other end of the ejector in position to permit ejection of a coin from said tube when the lever is depressed by pressing said button.

In testimony whereof I have hereunto subscribed my name in the presence of two subscribing witnesses.

GEORGE F. McGILL.
